CLAIM

The ornamental design for false nail, as shown and described.

DESCRIPTION

1. False nail

1.1 : Front

1.2 : Back

1.3 : Top

1.4 : Left

1.5 : Perspective

The article of the design is false nails; an concave/convex part is formed at the side of the false nails; the concave/convex part is attached onto the tip side of the nail when using the false nails; the bottom view of each design is omitted because it is a mirror image of the top view; the right view of each design is omitted because it is a mirror image of the left view.
